UNITED STATES PATENT OFFICE

JOHN M. HARPER, OF PHILADELPHIA, PENNSYLVANIA, ASSIGNOR TO HIMSELF AND A. COREY, OF SAME PLACE.

DEVICE FOR ARRANGING TYPE IN ROWS.

Specification forming part of Letters Patent No. **71,610**, dated December 3, 1867.

To all whom it may concern:

Be it known that I, JOHN M. HARPER, of Philadelphia, Pennsylvania, have invented certain Apparatus for Arranging Types in Rows; and I do hereby declare the following to be a full, clear, and exact description of the same.

My invention consists of the combination of a series of grooves for receiving the types, certain sliding blocks adapted to the grooves, an eccentric roller, and certain spouts, or their equivalents, the whole being arranged and operating substantially as described hereafter, for the purpose of enabling a type-distributer to arrange types of the same character in a row ready for introduction to the reservoir of the type-setting machine for which Letters Patent were granted to myself and Augustus Corey on the 30th day of April, A. D. 1867.

In order to enable others skilled in the art to make and use my invention, I will now proceed to describe the mode of constructing and using the same, reference being had to the accompanying drawing, which forms a part of this specification, and in which—

Figure 1 is a vertical section of my apparatus for arranging types of the same character in the same row; and Fig. 2, a transverse vertical section on the line 1 2, Fig. 1.

A is a table or platform, supported on suitable legs, *a a*, and on this table is a flat plate or board, B, on which are ribs or partitions *b*, arranged apart from each other, so as to form longitudinal grooves or channels for the admission of the type *x*. The plate B terminates abruptly at *m*, the upper corner being as close as possible to the surface of a roller, D, without being in absolute contact therewith. The roller is arranged eccentrically with its journals *e*, which turn in suitable bearings on the table A.

Opposite the front end of each groove or channel, between the ribs *b b* and above the roller D, is a spout, E, for receiving the type.

It will be understood that although I have shown but two grooves for receiving two rows of types, the table A is so wide that as many grooves may be formed as there are different types to distribute, one groove being devoted to type having the same letter, figure, or other device.

The eccentric roller D is caused to revolve in the direction of the arrow, and the distributor stations himself, with a mass of type in one hand, in front of the spouts E, and with his other hand takes type after type and drops them in the spout opposite the grooves in which they have to be arranged in rows. A type deposited in the spout slides down the same and comes in contact with the roller, assuming the position shown at *x'*, Fig. 1, from which position it is quickly drawn downward by the roller, owing to the eccentricity of the latter, until it rests with its lower end on the plate B, and is forced against the row of types *x*, previously introduced into the groove, the row bearing against a block, *y*, which, although arranged to slide freely in the groove, is of weight, and has friction sufficient on the same to maintain each type of the row in a vertical position.

The roller may have a surface of india-rubber, so as to have a better hold on the type and facilitate the dragging down of the same.

Although the above-described apparatus may be used to advantage for facilitating the proper *on* of type, especially when that duty has to be performed by young beginners, it is more especially useful as an adjunct to the type-setting machine for which Letters Patent were granted to myself and Augustus Corey, April 30, 1867, as the rows of type are arranged in proper order to be at once deposited in the several receptacles of the said type-setting machine.

I claim as my invention and desire to secure by Letters Patent—

The within-described grooves for receiving the type, and the sliding blocks *y*, in combination with the eccentric roller D and the spouts E, or their equivalents, the whole being arranged and operating substantially as and for the purpose herein set forth.

In testimony whereof I have signed my name to this specification in the presence of two subscribing witnesses.

JOHN M. HARPER.
